UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,121,106.

Specification of Letters Patent.

Patented Dec. 15, 1914.

Application filed June 4, 1914. Serial No. 843,048.

To all whom it may concern:

Be it known that I, JOHN KIEWICZ, a citizen of the United States, residing at Boston, county of Suffolk, State of Massachusetts, have invented an Improvement in Sewing-Machines, of which the following description, in connection with the accompanying drawing, is a specification, like characters on the drawing representing like parts.

This invention relates to blind stitch sewing machines of that type which employ a bender for forming bends in the work and while the stitches are being inserted where-
15 by a blind stitch will be produced, and particularly to the manner of mounting the bender and presser foot mechanism on the work support. There are blind stitch sewing machines of various types among which
20 might be mentioned those for finishing buttonholes, and in order to illustrate the invention I have shown it as it would be embodied in a blind stitch sewing machine of the so-called buttonhole-finishing type. Examples of sewing machines of this type are found in the following United States patents: No. 987,966, March 28, 1911; No. 1,047,537, December 17, 1912; No. 1,088,624, February 24, 1914. In sewing machines of
25 this type it is a desideratum to have the upper face of the work support as free as possible from projections, and also to so arrange the bender mechanism as to provide for high speed operation. In the above-mentioned
30 patents the bender is sustained on a carrier which is pivoted to the work support, thus obviating the necessity of an overhanging arm or bracket for sustaining the bender. In my present invention I have provided a
35 sewing machine of this type wherein the overhanging arm is omitted and the bender is sustained by a bender carrier pivotally secured to the work support and have mounted the bender carrier and presser foot in
40 such a way that the bearings therefor do not form any projection that stands above the face of the work support, and have also provided a construction wherein the bearing member for the bender carrier and presser
45 foot can be readily removed with these parts; and have also otherwise improved sewing machines of this type, all as more fully hereinafter described and then pointed out in the appended claims.

50 In the drawings wherein I have illustrated

a selected embodiment of my invention, Figure 1 is an under side view of a sewing machine made in accordance with my invention and showing the portions thereof which are essential to the invention; Fig. 2 is a section on substantially the line $x-x$, Fig. 1; Fig. 3 is a plan view of a portion of the bed of the machine; Fig. 4 is a section on the line $y-y$, Fig. 2, showing the construction of the bearing member.

The sewing machine herein shown comprises the usual base frame 1, the upper surface 2 of which constitutes a work support that is provided with the usual work-receiving groove into which the work is bent by 60 the bender. The bender for forming the bends in the work is shown at 3 and it is sustained on a bender carrier 4 in the form of a lever pivotally mounted on the bed frame 1 and actuated by a cam 5 on the 65 usual driving shaft 6 that is situated beneath the work support.

7 designates the presser foot which is sustained on a presser foot carrier 8 also pivotally secured to the bed frame 1 and yieldingly held against the work as usual in machines of this class.

In order to provide a construction which presents no projections above the surface of the work support and yet to provide proper 85 means for pivotally sustaining the bender carrier and presser foot carrier, I have herein shown said two parts as pivotally mounted in a bearing member 9 that is preferably detachably secured to the work support, and when in normal position has its top edge 90 flush with the work support, as shown in Fig. 2. As herein shown the work support is provided with an opening 10 of a size to receive the bearing member, and is formed 95 with lips or flanges 11 on which the bearing member rests, the latter being detachably secured to these lips or flanges in any suitable way as by means of screws 12. The bender carrier and presser foot carrier are both 100 herein shown as situated at one side of the bearing block and as projecting through openings in the work support. The bender carrier has a rock shaft 13 formed integral therewith and extending laterally therefrom 105 which has bearing in the bearing member 9, and said bender carrier is provided with the depending arm or portion 14 which is situated below the work support and carries at its lower end a roll 15 that engages the 110

bender-actuating cam 5 mounted on the driving shaft 6. This cam 5 is shown as a face cam, and the roll is held against said cam by means of a spring 17 which engages 5 a stud 18 extending from the arm 14. The rock-shaft 13 is held in this bearing by means of a washer 19 that is secured to the end of the shaft by a screw 20. The presser foot is also formed with a laterally-extending 10 rock-shaft 21 which is mounted in the bearing member 9 and extends substantially parallel to the rock-shaft 13, the presser-foot rock-shaft being herein shown as situated back of the bender rock-shaft. The rack-shaft 21 extends clear through the bearing member 9 and on its projecting end has an arm 22 fast thereto to which is connected a spring 23 that yieldingly holds the presser-foot against the work. In machines of this 15 class it is desirable that the presser foot should be raised from the work support when the machine is brought to rest, and the means by which this is herein accomplished is similar to that shown in my co-pending 20 application Se. No. 821,496, filed February 25, 1914.

The driving shaft 6 has thereon a stop cam 24 which coöperates with an arm 25 forming part of the stop mechanism which, 30 however, is only partially shown herein as it forms no part of the present invention. The arm 22 connected to the presser-foot rock-shaft carries a laterally-extending finger 26 which underlies the arm 25 and is normally held in engagement therewith by 35 the spring 23. The stop cam is so constructed that when the machine is brought to rest the stop cam 24 will force the arm 25 downwardly thereby acting through the finger 26 and arm 22 to actuate the presser-foot carrier to raise the presser-foot from 40 the work.

It will be noted that the bearing block 9 while of proper dimensions to give a sufficient bearing to the rock-shafts 13 and 21 is nevertheless flush with the top surface of the work plate and said bearing member, therefore, does not present any projections which rise above the work support. It will 45 also be noted that this bearing member is sustained in position on the lips or flanges 11 and can be readily removed from the top of the machine. The construction of the bender carrier and the presser-foot carrier 50 is such as to permit the bearing member with said bender carrier and presser-foot carrier to be readily removed from the machine if occasion arises, it merely being necessary to disconnect the spring 23 from 55 the arm 22 and remove the finger 26 from said arm. When this is done and the screws 60 12 have been removed the bearing member with the presser-foot carrier and bender-foot carrier can be readily removed from 65 the top of the machine. This is a decided

advantage because it does not necessitate the disconnection of any of the delicate parts of the machine.

In machines of this type it is of advantage to have the top surface of the work 70 support as free as possible from any projections which interfere with the free movement of the work, and this end is admirably accomplished in the construction herein set forth. 75

By the term "work support" as herein used, I have referred generally to the top of the base frame rather than to the particular portion with which the work has contact. 80

I claim:

1. In a sewing machine, the combination with a work support having an opening, of a driving shaft beneath the work support provided with a bender-operating cam, a bender carrier projecting through said opening and operated by said cam, a bender sustained by said bender carrier, and a bearing member removably secured to the work support at said opening and to which said bender carrier is pivoted. 85

2. In a sewing machine, the combination with a work support having an opening, of a bearing member removably sustained in said opening, a bender carrier pivoted to the bearing member and extending through and beneath the work support, and means beneath the work support to actuate the bender carrier, the top of the bearing member being substantially flush with the top of the 95 work support. 100

3. In a sewing machine, the combination with a work support having an opening, of a bearing member occupying said opening and removable from the top of the work 105 support, the top of the bearing member coming substantially flush with the top of the work support, a bender carrier pivoted to the bearing member and extending through and beneath the work support, and means 110 to actuate said bender carrier.

4. In a sewing machine, the combination with a work support having an opening, of a bearing member removably sustained in said opening, a bender carrier pivoted to the 115 bearing member and extending through and beneath the work support, means beneath the work support to actuate the bender carrier, the top of the bearing member being substantially flush with the top of the work 120 support, and a presser foot carrier also pivotally mounted on the bearing member. 125

5. In a sewing machine, the combination with a work support having an opening, of a bearing member removably sustained in 125 said opening with the top thereof coming substantially flush with the top of the work support, a bender carrier extending through and beneath the work support, said bender carrier having a rock-shaft integral there- 130

with which is journaled in the bearing member, and means acting on the lower end of the bender carrier to actuate the latter, said bender carrier being removable from the top 5 of the work support with the bearing member.

6. In a sewing machine, the combination with a work support having an opening, of a bearing member occupying said opening 10 and removable from the top of the work support, the top of the bearing member coming substantially flush with the top of the work support, a bender carrier pivoted to the bearing member and extending 15 through and beneath the work support, means to actuate said bender carrier, and a presser foot carrier also pivotally secured to and removable with the bearing member.

7. In a sewing machine, the combination 20 with a work support having an opening, of a bearing member removably sustained in said opening, a bender carrier pivoted to the bearing member and extending through and beneath the work support and being removable from the work support with the bearing member, and means beneath the work support to actuate the bender carrier.

8. In a sewing machine, the combination 25 with a work support having an opening, of a bearing member removably sustained in said opening, a bender carrier pivoted to the

bearing member and extending through and beneath the work support, the portion of the bender carrier below the bearing member extending substantially vertically where- 35 by the bender carrier can be removed from the work support with the bearing member, and means beneath the work support to actuate the bender carrier.

9. In a sewing machine, the combination 40 with a work support having an opening, of a bearing member removably sustained in said opening, a bender carrier pivoted to the bearing member and extending through and beneath the work support, a presser foot 45 carrier also pivoted to the bearing member and extending through and beneath the work support, the portions of the bender carrier and presser foot carrier that are situated below the opening in the work support 50 extending in a general vertical direction, and means beneath the work support to actuate the bender, said bender and presser foot carrier being removable from the work support with the bearing member. 55

In testimony whereof, I have signed my name to this specification, in the presence of two subscribing witnesses.

JOHN KIEWICZ.
